UNITED STATES PATENT OFFICE

134,341

DESIGN FOR A JOUSTING BOARD

Charles Harvey Churchill, Cortland, N. Y.

Application July 31, 1942, Serial No. 107,811

Term of patent 14 years

To all whom it may concern:

Be it known that I, Charles Harvey Churchill, a citizen of the United States, residing at Cortland, in the county of Cortland and State of New York, have invented a new, original, and ornamental Design for a Jousting Board, of which the following is a specification, reference being had to the accompanying drawing, forming part thereof.

Figure 1 is a top perspective view of a jousting board, showing my new design; and

Figure 2 is a bottom perspective thereof.

I claim:

The ornamental design for a jousting board, as shown.

CHARLES HARVEY CHURCHILL.
